MORTON L. JOHNSON, OF CHICAGO, ILLINOIS, ASSIGNOR, BY MESNE ASSIGNMENTS, TO
FRANK B. COOK COMPANY, OF CHICAGO, ILLINOIS, A CORPORATION OF ILLINOIS.

TELEPHONY.

1,109,167.

Specification of Letters Patent.

Patented Sept. 1, 1914.

Application filed October 9, 1912. Serial No. 724,754.

To all whom it may concern:

Be it known that I, MORTON L. JOHNSON, citizen of the United States, residing at Chicago, in the county of Cook and State of Illinois, have invented a certain new and useful Improvement in Telephony, of which the following is a full, clear, concise, and exact description, reference being had to the accompanying drawings, forming a part of this specification.

My invention relates to telephone exchange systems and has for its object the provision of improved automatic mechanism that may be set into operation by operators for the purpose of extending telephone lines.

As the invention is embodied calling telephone lines are extended into connection with called telephone lines that constitute the form of telephone line extensions with which my invention is of particular service, though I do not wish to be limited to the nature of the calling line extensions that are added to the calling lines nor do I wish to be limited to the extension of calling lines that extend to subscribers' stations in the practice of my invention.

In the preferred embodiment of the invention I employ link selector switches adapted to select idle link connectors which are to form parts of telephone circuits between telephone lines and their ultimate extensions. These link connector switches are set into operation by operator controlled switching mechanism and they are arrested in their operation jointly by the operator controlled switching mechanism and mechanism forming part of the link selector. Where connector switches are employed they are also set into operation by the operators' equipment and are arrested in connection with the waiting contacts that pertain to the called lines jointly by the operator controlled switching mechanism and mechanism forming part of the connector switches.

In practising the embodiment of the invention herein disclosed the portions of the link selector and connector switches that co-operate with operators' switching mechanism for the purposes stated are in the form of armature switches pertaining to relays or magnets entering into the formation of the selector and connector switches, though I do not limit myself to this characteristic in all embodiments of the invention.

The system herein disclosed is a species of

the generic invention set forth in my co-pending application Serial No. 724,753, filed October 9, 1912 (Case N).

The circuits for arresting the switches are individual to the extensions of the calling lines thereby affected and are individual to the various positions to which the circuit extending portions of the switches are placed so that troubles introduced by circuits that are common to more than one circuit for arresting the switches are eliminated.

In practising my invention the line extending switch is caused to operate a device which is adapted to operate in conjunction with one of a number of operator controlled devices that are individual to the different positions of the line extending switch to arrest the line extending switch in the position corresponding to the actuated operator controlled device. A switch controlled device is brought successively into such relation with the operator controlled devices that it will co-operate with the actuated one of the operator controlled devices for the purpose stated. These operator controlled devices are included in controlling circuits that are temporarily made individual to the different positions of the line extending switch and the different link connectors.

I will explain my invention more fully by reference to the accompanying drawings showing the preferred embodiment of the invention and in which—

Figure 1 is a simplified diagrammatic view disclosing my invention in outline; Figs. 2, 3, 4 and 5 taken collectively and in their numerical order, diagrammatically illustrate a telephone exchange system equipped in accordance with the invention, Figs. 2, 3 and 4 being read in connection with each other with the heavy conductors at the top portions thereof in alinement while Figs. 4 and 5 are read in connection with each other with the conductors extending lengthwise of Fig. 5 in alinement with the conductors discontinued at the right hand long side of Fig. 4.

The invention is clearly suggested by the diagram shown in Fig. 1, the portions of the system not illustrated in Fig. 1 being illustrated in the remaining figures. I will not describe Fig. 1 in detail owing to the description that will be given in connection with the remaining figures and in connection with which description of the remain-

ing figures Fig. 1 may readily be read as similar parts in the different figures have similar characters of reference.

In describing the invention as disclosed in Fig. 1, the party at the calling station, 211 for example, will, as a consequence of the removal of the receiver at the calling station from its switch hook, set the wipers of an automatically operating operator selector switch into operation until the wipers 1 and 2 of this automatically operating switch becomes arrested in connection with the telephone 5 connected to the waiting contacts engaged by the wipers 1 and 2 of the operator selector switch whereby such selected operator is able to communicate with the calling subscriber to ascertain the number of the line desired by the calling subscriber. Each operator has a key 6 that serves to set the wipers of a link selector switch A into operation, these wipers continuing to move vertically until they are arrested by means to be described. The vertical magnet 43 automatically operates to effect the elevation of the wipers of this selector switch A and in so doing intermittently operates the switch 7 to intermittently ground it against its contact thereby intermittently establishing a circuit that includes a controller magnet 8, the controller magnet 8, being intermittently energized, effecting the operation of the motor magnet 8¹ that effects the rotation of the arm or wiper 9. The arm 9 is thus brought to positive positions corresponding to the vertical positions of the wiper of the link selector switch A. Waiting contacts are located at the various positions to which the arm 9 is brought. These waiting contacts are connected with stationary contacts of operators keys that are distributed in three vertical rows B C D. The arm 9 is grounded so that the stationary contacts of the keys B C D are grounded when the waiting contacts with which the stationary contacts are connected are engaged by the grounded arm 9. Through the medium of electro-magnetic mechanism and circuits established by conjoint operation of the arm 9, its waiting contacts, and the keys in the row B, the operation of the relay 12 may be effected to arrest the vertical movement of the wipers of the switch A at a level corresponding to the level of the actuated key at B. The upper key in the row B serves to arrest the wipers of the switch A after they have been moved to the first level. The next key in this row serves to arrest these wipers in their second level, the next key in the third level, the next key in the fourth level, etc., there being as many keys in the row B as there are levels to which the wipers in the switch A may be stepped. After the wipers in the switch A have been brought to their proper level these wipers are automatically rotatively stepped

around until the wipers 13 and 14 engage the waiting contacts of the idle link connector that terminates in talking wipers 15 and 16. The key 6 will now serve to set the wipers 15, 16 and 17 of the connector switch into operation, these wipers continuing to move vertically until they are arrested by means to be described. The vertical magnet 70 of the connector switch automatically operating to raise the wipers of the connector switch until the magnet 70 is interrupted in its operation through the agency of the elements 8, 8¹, 9, and a key in the row C corresponding to the level at which the wipers of the connector switch are to be arrested, the vertical magnet 70 intermittently effecting the operation of an armature switch which co-operates with the relay 8 in a manner similar to the co-operation between the armature switch 7 and the relay 8. The upper key of the row C serves to arrest the wipers of the connector switch after they have been moved to the first level. The next key serves to stop these wipers at the second level, the next key in the third level, the next key in the fourth level, etc., there being as many keys in the row C as there are levels to which the wipers in the connector switch may be stepped. When the connector switch wipers have been brought to the level that contains waiting contacts belonging to the desired line, say the line extending to station 212, these wipers are stepped around until the wipers 15 and 16 engage the waiting contacts of the desired line. This result is accomplished with the aid of the key 6, and the circuit controlled by the rotary magnet 78 operating to effect the movement of the arm 9. When the wipers of the connector switch have been brought to the level containing the waiting contacts of the desired line, these wipers are automatically rotated as a consequence of the operation of the key 6 and suitably associated mechanism later to be described. The armature switch of the rotary magnet 78 is intermittently operated by this rotary magnet as said magnet performs its function in order intermittently to establish circuit through the relay 8 thereby to effect the step by step movement of the arm 9, this operation of the arm 9 being similar to that effected by the vertical magnet 70 and the vertical magnet 43. The rotation of the wipers 15, 16, etc., ceases when circuit has been established through the arm 9 and the depressed key in the row D corresponding to the waiting contacts of the desired line in the level over which the wipers of the connector switch are moving.

I will now more fully describe my invention by reference to Figs. 2 and 5 inclusive.

When the calling subscriber at station 211 (Fig. 3) removes his receiver 19 from its switch hook 20 a circuit is closed at the

switch hook 20 and its alternate contact which may be traced from the grounded common battery 21, the upper winding of relay 22, the uppermost armature switch of relay 23 and its normal contact, the upper intermediate armature switch of relay 24 and its normal contact, both sides of the calling line, the lower intermediate armature switch of relay 24 and its normal contact, the lower armature switch of relay 23 and its normal contact, to the lower grounded coil of relay 22. The relay 22 thereupon attracts its armature switches, circuit being established which may be traced from the intermediate grounded armature switch of relay 22 and its alternate contact, the armature switch of the sluggishly operating relay 25, the winding of this relay, the winding of rotary magnet 26, the side switch wiper 27, to the grounded battery 21, the illustration of this battery being repeated many times for the sake of clearness. When the rotary magnet 26 is energized it sets wipers 1, 2, 28 and 29 of the operator selector switch 20 into operation until the wiper 29 encounters an ungrounded waiting contact whereupon these wipers will become arrested with the wipers 1 and 2 engaging the waiting contacts constituting terminals of conductors 25 leading to an idle operator's telephone 5. The wipers 1, 2, 28 and 29 are arrested as described owing to the opening of the circuit for the private magnet 30 when the wiper 29 engages an ungrounded waiting 30 contact, the circuit for this magnet 30 having been initially established upon the initial energization of the rotary magnet 26. When the private magnet 30 is deenergized the side switch wipers 27 and 31 are stepped 35 into their second and final positions. The side switch wiper 31 is grounded, when in its second position, so as to ground the waiting contact engaged by the wiper 29 and all other similarly positioned multiply related 40 contacts of other operator selector switches so that no operator selector switch can be operated by any other calling subscriber in a manner to become connected with the operator's telephone 5 that has become connected with the calling subscriber 211. When the side switch wiper 27 is in its second position circuit for the rotary magnet 26 is opened so that the wipers 1, 2, 28 and 29 will remain with the wipers 1 and 2 in 45 connection with the telephone 5. A signal 32 may be employed at each operator's position to have circuit closed therethrough when an operator's telephone 5 is selected in the manner which has been described, circuit 50 governing this signal 32 being traceable from the side switch wiper 31 when grounded in its second position, the wiper 29, the waiting contact engaging the same, the winding of relay 33, to the grounded battery 21. The relay 33 thereupon attracts its 55 armature switch to close circuit for the signal 32, which circuit is apparent. The operator being in telephonic communication with the calling subscriber ascertains the wants of the calling subscriber and for the sake of illustration it is assumed that the calling subscriber desires communication with the subscriber at station 212. The operator will depress the second key from the top of row B, the top key of row C, and the second key from the top of row D, these keys remaining depressed either by the hand of the operator or by automatically released means, whereafter the operator momentarily depresses the self-releasing key 6 (see Fig. 2). Key 6, though the last depressed, is the first to become effective, it serving to effect the elevation of the wipers of the link selector switch A (Fig. 4). The key 6, when depressed establishes a circuit which may be traced from the grounded spring of this key, the two contacts to the right of this spring that are connected when the key is depressed, the follow-up normal contact of the armature switch immediately to the right of the relay 34, to the grounded battery 21. This armature switch engages its alternate contact to establish a locking circuit through the relay 34, which locking circuit may be traced from the grounded battery 21, the relay 34, the said armature switch and its alternate contact, to the left hand grounded armature switch of the sluggishly operating relay 35. A circuit is also established that may be traced from the grounded spring of the key 6, the contact next adjacent thereto, the winding of sluggishly operating relay 36, to the grounded battery 21. When relay 36 is energized it establishes a circuit which may be traced from the grounded battery 21, the alternate contact of the right hand armature switch of this relay 36, the second armature switch to the right of relay 34 and its alternate contact, the talking wiper 2 and the waiting contact engaged thereby, the intermediate armature switch of relay 37 and its normal contact, the winding of relay 38, the intermediate armature switch of private magnet 30, and its normally engaged contact, to the grounded lower coil of relay 22. The relay 38 is thereupon operated to establish a circuit which is traceable from the grounded battery 21, the armature switch of relay 38, the winding of relay 37, to ground. A locking circuit is established for relay 37 which is traceable from the grounded coil of this relay through its lowermost armature switch and its now engaged contact, the contact engaged by the side switch wiper 27 in its second position, said side switch wiper, to the grounded battery 21. When relay 37 is operated it breaks connection between the calling line and the operator at the two upper armature switches of relay 37 interposed between the wipers 1 130

and 2 and the calling substation. By breaking the circuit at the upper armature switches of relay 37, calling line equipment is disconnected from the talking conductors leading from these armature switches to the second and third armature switches at the right of relay 34, and as the operator's telephone 5 is now disconnected from these telephone conductors such telephone conductors 5 may be employed in effecting connection between calling and called lines. The sluggishly operating relay 36 becomes restored, after the key 6 is released and restores itself, as a consequence of which the circuit is established which is traceable from the left hand grounded armature switch of relay 36 and its engaged contact, the left hand armature switch of relay 34 and its engaged contact, the right hand armature switch of relay 39 and its normally engaged contact, the winding of relay 40, to the grounded battery 21. When the relay 40 is thus energized a circuit is established which is traceable from the left hand grounded armature switch of relay 40, 10 its then engaged contact, the right hand armature switch of sluggishly operating relay 41, and its normally engaged contact, the armature switch of relay 36 and its now engaged contact, the third armature switch 15 from the right of relay 34 and its now engaged alternate contact, the talking conductor leading to the waiting contact now engaged by the wiper 1, the wiper 1, the upper armature of relay 37 and its alternate contact, the upper intermediate armature switch of relay 42 and its normal contact, the winding of relay 12, to the grounded battery 21. Circuit for the vertical magnet 43, that is employed to elevate the wipers 13, 20 14 and 44, is now established and may be traced from the grounded battery 21 through the circuit interrupter 45, the vertical magnet 43, the lower intermediate armature switch of relay 46 and its normally engaged contact, the lowermost armature switch of relay 12 and its now engaged contact, the lowermost armature switch of relay 42, to ground. The vertical magnet 46 is intermittently energized owing to the circuit interrupter 45 and is therefore intermittently operated to step the wipers 13, 14 and 44 to different levels. Owing to the circuit interrupter 45, the wipers of the switch A pause in each of the levels to which they have been 25 raised a sufficient length of time to permit the vertical magnet 43 properly to operate the relay 8, to permit the relay 8 to close the circuit of the motor magnet 8¹ at a sufficiently slow rate of speed so that the magnet 8¹ will operate at a sufficiently slow rate of speed to permit the arm 9 to remain in engagement with its waiting contacts during suitable periods, in which periods the electro-magnetic mechanism whose circuits 30 65 are governed by the arm 9 may properly

operate. The circuit established by the vertical magnet 43 through the relay 8 is traceable from the grounded contact of the armature switch 7, this armature switch, the lower intermediate armature switch of relay 42 and its normal contact, the intermediate armature switch of the relay 37 and its alternate contact, the wiper 2 and the contact engaged thereby, the second switch to the right of relay 34 and its alternate contact, the right hand switch of relay 36 and its normal contact, the winding of relay 8 to the grounded battery 21. The relay 8 attracts its armature switch to close the obvious circuit through the motor magnet 8¹. The motor magnet 8¹ has its armature provided with an actuating pawl that moves the ratchet wheel 8² as the motor magnet 8¹ is intermittently energized. The arm 9 is fast upon the shaft of the ratchet wheel 8². In the connection between calling and called subscribers that is being described the vertical magnet 43 is to be operated but twice in order to bring the wipers 13, 14 and 44 of the switch A to the second level, to which end the second key from the top of the row B is depressed to prevent these wipers from moving higher than the second level, the switch arm 9 establishing a circuit when it is engaged with its second waiting contact 95 which is traceable from the grounded arm 9, the second waiting contact engaged thereby, the stationary contact of the second key from the top row B, the contact spring of this key, the sluggishly operating relay 41, 100 the now attracted right hand armature switch of relay 40 to the grounded battery 21. Circuit for the relay 12 is consequently opened at the right hand armature switch of relay 41. When the circuit of relay 12 is 105 opened its armature switches are released and a ground is momentarily applied to the coil of relay 46 owing to the sluggish release of relay 47 which has its circuit previously closed at the upper armature switch 110 of relay 12 and the alternate contact of this armature switch. Circuit for relay 46 is traceable from the grounded battery 21, the winding of relay 46, the still attracted armature switch of sluggishly operating relay 47, 115 the upper armature switch of relay 12, to ground by way of the normal contact of this latter armature switch. A locking circuit is established for relay 46 which is traceable from the grounded 120 battery 21, the winding of the relay 46, the upper intermediate armature switch of relay 46 and its now engaged contact, the uppermost armature switch of relay 42 and its normal follow-up contact, to the right hand grounded armature switch of sluggishly operating relay 48; which armature switch has been attracted to engage its contact, circuit for the relay 48 having been 125 previously established at the lowermost 130

armature switch of relay 22. The circuit for the vertical magnet 43 has now been opened at two points, the lower intermediate armature switch of relay 46 and the lower armature switch of relay 12 so that the wipers of the switch A remain in the level in which they have been brought. The relay 46, when it is energized, includes the rotary magnet 49 in a circuit which is traceable from the grounded battery 21, the circuit interrupter 50, the winding of the rotary magnet 49, the lowermost armature switch of relay 46, to the lowermost grounded armature switch of relay 42. The rotary magnet 49 operates to rotate the wipers of the link selector switch A until these wipers engage the idle link circuit, that is until the wiper 44 engages a waiting contact which is connected with ground through battery and which has no direct connection with ground, the waiting contacts of the wiper 44 being directly grounded when the link circuits associated with these waiting contacts are busy and being grounded only through battery when these link circuits are idle. When the wiper 44 engages a waiting contact that is not directly grounded, the sluggishly operating relay 51 is energized by a circuit traceable from the grounded battery 21 (Fig. 5) the winding of sluggishly operating relay 52, the normal follow-up contact of the upper armature switch of relay 53 and said armature switch, the waiting contact engaged by the wiper 44, the uppermost armature switch of relay 46 and its alternate contact, the winding of sluggishly operating relay 51, to ground. The relay 51 thereupon establishes a circuit which is traceable from its grounded armature switch, the contact engaged thereby, the winding of relay 42, to the grounded battery 21. The relay 42 establishes a locking circuit which may be traced from the grounded battery 21, the winding of the relay 42, the uppermost armature switch of this relay and its alternate contact, the armature switch of relay 48 and its then engaged contact to ground. When the relay 42 is energized it opens the circuit for the rotary magnet 49 at the lowermost armature switch of relay 42 whereupon the wipers are brought to rest in connection with the idle link circuit. When the link circuit is busy the associate waiting contacts belonging to the wiper 44 are connected directly with ground either at the armature switch of relay 48 (Fig. 3) or at the uppermost armature switch of energized sluggishly operating relay 54, which relay 10 is energized by a circuit traceable from the grounded battery 21, the winding of the relay 54, to ground, the relay 55 having been energized in a manner which will later be described. When the buttons of the 35 wiper 44 are limited to direct connection

with ground the relay 51 will obviously not be energized so that the rotary magnet 49 will continue in operation. When relay 42 is energized the locking circuit for the relay 46 is broken by the separation of its upper armature switch from its normal follow-up contact whereby the relay 46 is restored to normal, the deenergization of the relay 46 enabling the grounded armature switch 48 to become connected with the wiper 44 by a path traceable from the grounded armature switch of relay 48, the uppermost armature switch of relay 42 and its alternate contact, the uppermost armature switch of relay 46 and its normal contact, to said wiper 44. When the relay 42 is energized the intermediate armature switches thereof connect the talking wipers 13, 14 with the wipers 1 and 2. When the relay 41 (Fig. 2) is energized a circuit is established which may be traced from the grounded contact of the intermediate armature switch of this relay and said armature switch, the normal follow-up contact of the intermediate armature switch of relay 39 and this armature switch, the winding of relay 39, to ground by way of battery 21. A locking circuit is established for the relay 39 which is traceable from the grounded battery 21, the winding of relay 39, the intermediate armature switch of this relay and its alternate contact, the left hand armature switch of relay 34 and its previously engaged contact, to the left hand grounded armature switch of relay 36 and its contact. When the relay 41 is energized its left hand armature switch establishes a circuit traceable from its grounded contact and this switch, the normal follow-up contact of the right hand armature switch of relay 8², the winding of this relay to the grounded battery 21. The relay 8² establishes a locking circuit for itself traceable from the grounded battery 21, through the relay 8², the alternate contact of the right hand armature switch of this relay, the arm 8⁴, to the grounded contact engaged by this arm when the ratchet wheel 8² is moved upon its first step. The left hand armature switch of relay 8³ establishes the obvious circuit through the release magnet 8⁵, this release magnet withdrawing the holding pawl from engagement with the ratchet wheel 8² so that the coiled spring with which the ratchet wheel is provided may restore its ratchet wheel to normal position as illustrated in Fig. 2, whereby the contact arm 9 is restored to the normal position illustrated. When the parts are in normal position the arm 8⁴ has been disengaged from its grounded contact so that the locking circuit for the relay 8² is open. When relay 39 is energized circuit for relay 40 is opened at the right hand armature switch of relay 39. When the relay 40 is 130

thus deenergized ground is removed at its left hand armature switch from the conductor leading to the waiting contact engaged by wiper 1. Circuit for relay 41 is also 5 opened at the right hand armature switch of relay 40 to prevent faulty operation of relay 41. When the relay 39 is energized a circuit is established at its left hand armature switch that may be traced from the 10 grounded brush 56, the disk 57 engaged by the brush 56, the brush 58 engaged with the disk 57 momentarily once in each revolution of the disk 57 which is rotated by a motor 59, the left hand armature switch of 15 relay 39 and its contact, the left hand armature switch of relay 60 and its normal follow-up contact, the winding of relay 60, to the grounded battery 21. A locking circuit is established for the relay 60 which is traceable 20 from the grounded battery 21, the winding of relay 60, the left hand armature switch of this relay and its alternate contact, the left hand armature switch of relay 34 and its then engaged contact, to the left hand grounded armature switch of 25 relay 36 and its then engaged contact. The relay 60, when thus energized, effects the establishment of a circuit which is traceable from the brush 61, the driven disk 62, 30 the brush 63 momentarily engaged with the disk 62 once in each revolution of such disk, the right hand armature switch of relay 60 and its then engaged contact, the right hand armature switch of relay 64 35 and its follow-up contact, the winding of relay 64, to the grounded battery 21. A locking circuit is established for the relay 64 which is traceable from the grounded battery 21, the winding of the relay 64, 40 the right hand armature switch of this relay and its alternate contact, the intermediate armature switch of relay 60 to its grounded contact. When the relay 64 is energized a circuit is established which is traceable 45 from its left hand armature switch and the grounded contact then engaged thereby, the right hand armature switch of relay 65 and its engaged contact, the winding of relay 66, to the grounded battery 21. The relay 50 66, when energized establishes a circuit traceable from its left hand grounded armature switch and the contact engaged thereby, the right hand armature switch of sluggishly operating relay 67 and the contact 55 engaged thereby, the intermediate armature switch of relay 36 and the contact engaged thereby, the third armature switch to the right of relay 34 and the alternate contact engaged thereby, the waiting contact engaged 60 by the wiper 1, the upper armature switch of relay 37 and its alternate contact, the upper intermediate armature switch of relay 42 and its alternate contact, the wiper 13, the upper intermediate armature switch 65 of relay 68 and its normal contact, the wind-

ing of relay 69, to the grounded battery 21. Circuit for the vertical magnet 70 of the connector switch is consequently included in a closed circuit traceable from the grounded battery 21, the interrupter 71, the winding of the vertical magnet 70, the sluggishly operating relay 72, the lower armature switch of relay 73 and its normal contact, the lower armature switch of relay 69 and its contact, to the grounded lower armature switch of relay 53, and its contact. 70

The vertical magnet 70 is intermittently energized, as a result of the operation of the circuit interrupter 71, to bring the wipers of the connector switch to the level containing the waiting contacts of the desired or to be called line. The extent to which the wipers of the connector switch may be elevated is determined by the key in the row C which has been depressed. In this case, the 80 called subscriber being No. 212, the uppermost key in the row C has been depressed so that when the wipers of the connector switch have been raised to the first level they will be raised no further. This is owing to the 85 establishment of a circuit traceable from the grounded armature switch of the vertical magnet of the connector switch and its engaged contact, the lower intermediate armature switch of the relay 68 and its normal 90 contact, the wiper 14 of the switch A and its engaged waiting contact, the lower intermediate armature switch of the relay 42 and its alternate contact, the intermediate armature switch of the relay 37 and its alternate 95 contact, the wiper 2 and its engaged waiting contact, the second switch from the right of relay 34 and its alternate contact, the right hand armature switch of relay 36 and its normal contact, the relay 8, to the grounded 100 battery 21, the relay 8 operating to move the arm 9 through the intermedium of the relay and electro-magnetic mechanism previously described. The arm 9 is moved to the first waiting contact accompanying the 110 vertical movement of the wipers of the connector switch to their first level and as the top key of row C has been depressed in order to arrest the wipers of the connector switch at the first level, a circuit is established 115 which is traceable from the grounded arm 9 and the first contact engaged thereby, the stationary contact of the upper key in row C and the winding of sluggishly operating relay 67, the right hand armature switch of relay 66, to the grounded battery 21 by way of the grounded contact. When the relay 67 is energized the circuit which was previously traced from the left hand armature switch of relay 66 and the relay 69 is open at the right hand armature switch of relay 67. When the circuit of relay 67 is opened, its upper grounded armature switch engages its contact, a circuit being momentarily established through relay 73 owing to 120 125 130

the sluggishness of relay 72, this circuit being traceable from the upper grounded armature switch of relay 69 and its contact, the armature of sluggishly operating relay 72 and its contact, the winding of relay 73 to the grounded battery 21. The relay 73 establishes a locking circuit for itself which is traceable from the grounded battery 21 through the winding of the relay 73, the upper armature switch of this relay and its contact, the upper armature switch of relay 53 and its normal follow-up contact, the wiper 44 and its engaged waiting contact, the upper armature switch of relay 46 and its normal contact, the upper armature switch of relay 42 and its alternate contact, the armature switch of relay 48 and its contact, to ground. When relay 73 is energized circuit for the vertical magnet 70 is opened at the lower armature switch of relay 73 and its normal contact, such circuit also being opened at the lowermost armature switch of relay 69 whereby vertical movement of the wipers of the connector switch ceases, these wipers having been brought to the level which contains the waiting contacts of the desired line. When the relay 67 is energized its left hand armature switch operates to effect the restoration of the arm 9 to normal in a manner similar to that which was described in connection with the left hand armature switch of relay 41. When relay 67 was energized it established a circuit at its intermediate armature switch traceable from the grounded contact of this armature switch through the switch, the intermediate armature switch of relay 65 and its normal follow-up contact, the winding of this relay, to the grounded battery 21. The relay 65 establishes a locking circuit for itself which is traceable from the grounded battery 21 through its intermediate armature switch, the alternate contact of this switch, to the left hand armature switch of relay 64 and its then engaged grounded contact. When relay 65 is energized a circuit is established traceable from the grounded brush 56 through the disk 57, the brush 58 when engaging the disk, the left hand armature switch of relay 65 and its engaged contact, the left hand armature switch of relay 74 and its normal followup contact, the winding of relay 74, to the grounded battery 21. The relay 74 establishes a locking circuit for itself traceable from the grounded battery 21 through the winding of relay 74, the left hand armature switch of this relay and its alternate contact, the left hand armature switch of relay 34 and its engaged contact, to the left hand grounded armature switch of relay 36 by way of its engaged contact. The relay 74, having been energized, establishes a circuit traceable from the grounded brush 61, the disk 62, the brush 63 when engaging the disk, the right hand armature switch of relay 74 and its engaged contact, the normal follow-up contact of the right hand armature switch of relay 75, to the grounded battery 21. The relay 75 establishes a locking circuit for itself traceable from the grounded battery 21 through the winding of the relay, the right hand armature switch of this relay, the alternate contact of this armature switch, the intermediate armature switch of relay 74, to the grounded contact engaged by this intermediate armature switch. Relay 75 now establishes a circuit traceable from the grounded battery 21 through the relay 76, the left hand armature switch of relay 75, to the grounded contact engaged by this armature switch. The relay 76 establishes a circuit traceable from its left hand grounded armature switch, the contact engaged thereby, the right hand armature switch of sluggishly operating relay 77 and the contact engaged thereby, the intermediate armature switch of relay 36 and the contact engaged thereby, the third armature switch from the right of relay 34 and the alternate contact engaged thereby, the wiper 1 and the waiting contact engaged thereby, the upper armature switch of relay 37 and the alternate contact engaged thereby, the upper intermediate armature switch of relay 42 and the alternate contact engaged thereby, the wiper 13 and the waiting contact engaged thereby, the upper intermediate armature switch of the relay 68 and the normal contact engaged thereby, the relay 69, to the grounded battery 21. The relay 69 now establishes a circuit for the rotary magnet 78 which serves to rotate the wipers of the connector switch, this circuit being traceable from the lower grounded armature switch of relay 53 and the contact engaged thereby, the lower armature switch of relay 69 and the contact engaged thereby, the lower armature switch of relay 73 and the alternate contact engaged thereby, the sluggishly operating relay 79, the rotary magnet 78, the interrupter 71, to the grounded battery 21. The wipers of the connector switch now rotate step by step in the level to which they were previously raised until the wipers of the connector switch are rotated to engage the waiting contacts belonging to the desired line. To this end the rotary magnet 78 is caused intermittently to establish circuit through the relay 8 in a manner which will now be understood to effect the step by step movement of the arm 9 by the apparatus which has been described. When the arm 9 has been stepped to engage its second waiting contact, a circuit is established (owing to the depression of the second key from the top of the row D) which is traceable from the grounded arm 9, the second waiting contact engaged thereby, the stationary contact of the key second from the top of the row D, 139

the contact spring of this key, the winding of sluggishly operating relay 77, the right hand armature switch of relay 76, to the grounded battery 21 by way of the contact of this switch. When the relay 77 is energized it opens circuit for the relay 69 to arrest the wipers of the connector switch in engagement with the second waiting contacts in the first level, these contacts pertaining to the 10 telephone line extending to the called station 212. The left hand armature switch of the energized relay 77 operates to restore the arm 9 to normal this operation being similar to that described as having been accomplished by the left hand armature switch of relay 41. When the relay 69 is deenergized its upper armature switch establishes a circuit which is traceable from ground, the upper armature switch of relay 69, the contact engaged thereby, the right hand armature switch of sluggishly operating relay 79, the winding of relay 53, the winding of relay 68, to the grounded battery 21.

The relay 53 establishes a locking circuit 25 for itself and for the relay 68 which is traceable from the grounded battery 21, the windings of these two relays, the upper armature switch of relay 53 and its right hand alternate contact, the wiper 44 and the waiting 30 contact engaged thereby, the uppermost armature switch of relay 46 and its normal contact, the uppermost armature switch of relay 42 and its alternate contact, the right hand armature switch of relay 48 and its 35 contact, to ground. Circuit for the rotary magnet 78 is now open at the lower armature switches of the relays 53 and 69 so that the wipers of the connector switch are arrested with the wipers 15 and 16 in connection 40 with the waiting contacts belonging to the desired line No. 212. It will be observed that the disks 57 and 62 have peripheral projections for engagement with the brushes 58 and 63. These peripheral 45 projections are so angularly displaced that a considerable interval of time will elapse between the connection of the brush 58 with the disk 57 and the subsequent connection of the disk 62 with the brush 63. I preferably 50 cause this time interval to be about one second in duration. This interval of time will be sufficient to allow the wipers of the idle link selector switch A to seek an idle link after these wipers have been raised 55 to the desired level. This time interval is also employed to enable the relays of the connector switch to perform their switching functions after the wipers of the connector switch have been raised to their desired 60 level. The relay 77 establishes a circuit at its left hand armature switch through the sluggishly operating relay 35. The energized relay 35 establishes a circuit which may be traced from the grounded battery 21, the right hand armature switch of relay

35, the wiper 28 and the contact engaged thereby, the lowermost armature switch of the private magnet 30 and its engaged contact, the relay 24, to the grounded armature switch of relay 48 by way of its contact. 70 The relay 24 establishes a locking circuit for itself traceable from the grounded battery 21, through the lowermost armature switch of relay 24 and its engaged contact, the winding of relay 24, the armature switch of relay 48 and its contact, to ground. When the relay 24 is operated the ground connection previously established by the relay 48 for establishing the circuit of the relay 24 is removed but is replaced by the grounded 75 upper armature switch of the sluggishly operating relay 54 in a manner to be described. When relay 24 is energized circuit for relay 22 is opened at the intermediate armature switch of relay 24 whereby the relay 22 is deenergized to release its armature switches. Circuit for the release magnet 80 of the idle operator selector switch is established at the intermediate armature switch of relay 22 when engaging its normal contact, the off 80 normal switch 81 having previously been closed. All of the wipers 1, 2, etc., of the idle operator selector switch are now restored to normal. The relay 37 is consequently deenergized completing the restoration 85 to normal of all of the equipment of the idle operator selector switch that was employed to connect the calling subscriber 90 211 with the telephone equipment 5. The attracted left hand armature switch of relay 35 opens the locking circuit for the relay 34 to restore it to normal. Locking circuits for the relays 39, 60 and 74 are opened at the left hand armature switch of the deenergized relay 34 to restore these relays 95 100 60 and 74 to normal. The relays 64, 65, 75 and 76 are consequently restored to normal whereby all of the operator's equipment which was employed in extending the calling line is restored to normal. When the 105 wiper 29 is restored to normal circuit for the relay 33 is opened to restore it to normal. When relay 24 is energized it connects the sides of the calling line, at its intermediate armature switches, with the talking conductors leading to the wipers 13 and 14 by way of the alternate contacts of the intermediate armature switches of the relay 24. When relay 68 is energized its armature switches are attracted to become connected with their alternate contacts whereby the waiting contacts engaged by the wipers 110 115 120 125 13 and 14 are connected with the talking conductors that extend to the talking wipers 15 and 16. When the relay 68 was energized it established a circuit through the relay 55 traceable from the grounded battery 21, the upper winding of relay 55, the normally positioned armature switch of relay 82 and its contact, the upper intermediate armature

switch of relay 68 and its alternate contact, the wiper 13 and its engaged waiting contact, the upper intermediate armature switch of relay 42 and its alternate contact, the upper intermediate armature switch of relay 24 and its alternate contact, the telephone receiver, transmitter and switch hook at the calling station 211 and the alternate contact of this switch hook, the lower intermediate armature switch of relay 24 and its alternate contact, the lower intermediate armature switch of relay 42 and its alternate contact, the wiper 14 and its engaged waiting contact, the lower intermediate armature switch of relay 68 and its alternate contact, to the grounded lower coil of relay 55. The relay 55 serves to energize relay 54 by a circuit established by way of the upper armature switch of relay 55. When relay 54 is energized its upper grounded armature switch engages its contact to replace the ground removed at 48 from the relays 24, 42, 53 and 68. When the wipers of the connector switch have become connected the called line wiper 83 of the connector switch establishes a circuit which may be traced from the grounded battery 21, the winding of relay 84, the alternate contact of the armature switch of relay 85, the wiper 83, the uppermost armature switch of relay 24 pertaining to the called line and its normal contact (Fig. 3), the uppermost armature switch of relay 22 pertaining to the called line and its normal contact, the relay 23 pertaining to the called line, to the grounded battery 21, the circuit for relay 85 having previously been momentarily established at the lower contact of the sluggishly operating relay 79 and the released upper armature switch of relay 69. The relay 84 will not be energized if the desired line is free for connection with the calling line since the upper terminal of the winding of relay 84 is not connected with any direct ground when the desired line is free but is only connected with the same terminal of the battery 21 with which the lower terminal of the winding of relay 84 is connected. When the desired line is busy the upper terminal of relay 84 is connected directly with ground at the upper armature switch of relay 54 of another connector switch in case the desired line is a previously called line. If the desired line is itself a calling line the upper terminal of the relay 84 is connected directly with ground at the uppermost armature switch of relay 24 pertaining to the desired line and the alternate contact of this uppermost armature switch or, at one stage of the connection, this direct ground is established by the uppermost armature switch of relay 22 pertaining to the desired line and its alternate grounded contact. When the relay 84 is energized, which is the

case when the desired line is busy, it establishes a locking circuit for itself which is traceable from the grounded battery 21, the winding of relay 84, the armature switch immediately above the winding of relay 84 and the contact engaged by this armature switch, the upper armature switch of relay 54 and the contact then engaged thereby, to ground. The relay 84 then becomes effective to place a busy tone upon the telephone circuit leading back to the calling line. This busy tone test is applied to the line by means of the bridge connection established between the talking sides of the line leading back to the calling line, which bridge connection may be traced from the alternate contact of the lower intermediate armature switch of relay 84, the condenser 86, the secondary 87, to the alternate contact of the second armature switch above the winding of relay 84. The busy tone is effected by means of the circuit interrupter 88 in circuit with the primary 89 and the battery 21. In the event of such a busy tone the calling subscriber restores his telephone receiver upon its switch hook to restore the equipment which was employed to effect the transfer of the busy tone to the calling station, the restoration of this apparatus being explained later.

Assuming that the desired line is free for use the relay 84 will remain inert and the cutoff relay 23 pertaining to the desired line 212 will be energized so as to prevent the operator selector switch associated with the calling line from being operated when the called party responds. The circuit for the relay 23 pertaining to the called line thus established is traceable from the grounded battery 23 through the winding of relay 23 of the called line, the uppermost armature switch of relay 22 of the called line and its normal contact, the uppermost armature switch of relay 24 and its normal contact, the wiper 83 and its engaged waiting contact, the armature switch of relay 85 and its normal contact, the uppermost armature switch of relay 84 and its contact, the upper armature switch of relay 53 and its left hand alternate contact, to the grounded upper armature switch of relay 54 and its engaged contact. The called subscriber's signal bell 90 is included in circuit with the generator 91 owing to the energization of the relay 92 which was effected by a circuit traceable from the lower grounded armature switch of relay 55 and its engaged contact, the lower switch of relay 84, and its engaged contact, the lower switch of relay 93 and its engaged contact, the winding of relay 92, to the grounded battery 21. The relay 92, when energized, establishes a signaling circuit through the called subscriber's bell 90, which circuit may be traced from the right hand pole of the ringing

generator 91, the alternate contact of the upper armature switch of relay 92, the wiper 16 of the connector switch and its engaged waiting contact, the lower armature switch 5 of relay 23 of the called line and its alternate contact, the lower intermediate armature switch of relay 24 of the called line and its normal contact, the switch hook 20 of the called line, the normal contact of this 10 switch hook, the condenser 94 (employed to maintain circuit through the relay 22 normally open when the telephone receiver is upon the switch hook), the signal bell 90, the upper intermediate armature switch of 15 relay 24 of the called line and its normal contact, the upper armature switch of relay 23 of the called line, and its alternate contact, the wiper 15 of the employed connector switch and the waiting contact engaged thereby, the upper armature switch 20 of relay 92 and its alternate contact, the winding of relay 95, the circuit interrupter 96 employed to effect intermittent operation of the signal 90, back to the generator 91. 25 The relay 95 is of such resistance and adjustment that it will not be operated by current passing from the generator 91 through the called subscriber's bell 90 and the associate condenser 94. When the called subscriber removes his telephone from its 30 switch hook the continuous path through the called subscriber's receiver and transmitter is substituted for the path including the condenser 94 and bell 90, this substitute 35 path being of sufficiently low resistance to permit the current from generator 91 operatively to energize the relay 95. When the relay 95 is energized a circuit is established which is traceable from its grounded armature switch and the contact then engaged thereby, the winding of relay 93, to the 40 grounded battery 21. When the relay 93 is energized it establishes a locking circuit for itself traceable from the grounded battery 21, the intermediate armature switch of 45 relay 93 and its engaged contact, to the grounded upper armature switch of relay 54 by way of its engaged contact. When the relay 93 is energized it opens a circuit at 50 its lower armature switch for the relay 92. The relay 92 thereupon releases its armature switches to cut the generator 91 out of circuit, to connect the talking wipers 15 and 16 of the connector switch with the sides of 55 the calling line in a manner that will be understood from the diagram and to restore the relay 95. When the called subscriber responds a circuit is established through the relay 97 which may be traced from the lower 60 grounded terminal of this relay through the lowermost armature switch of relay 68 and its engaged contact, the lower intermediate armature switch of relay 84 and its normal contact, the lower armature switch of relay 92 and its normal contact, the talking wiper 65 16 of the connector switch, the lower armature switch of relay 23 of the called line and its alternate contact, the lower intermediate armature switch of the relay 24 of the called line and its normal contact, the switch hook 20 of the called line and its alternate contact, the telephone receiver and transmitter at the called station, the upper intermediate armature switch of relay 24 of the called line and its alternate contact, the wiper 15 of the connector switch and its engaged waiting contact, the upper armature switch of relay 92 and its normal contact, the second switch from the top of the winding of relay 84 and its normal contact, the uppermost switch of relay 68 and its engaged contact, the upper winding of relay 97 to the grounded battery 21. A second circuit is now established for the relay 54 traceable from the lower grounded switch of the relay 97 and its engaged contact, the winding of relay 54, to the grounded battery 21, whereby this relay 54 is under the joint control of the calling and called stations and is not deenergized until the receivers at both 90 stations are restored upon their switch hooks. When both subscribers have restored their receivers upon their switch hooks the calling subscriber's relay 55 and called subscriber's relay 97 are deenergized so that 95 both energizing circuits for the relay 54 are open and this relay 54 is deenergized. The upper grounded armature switch of relay 54 is thus disconnected so as to remove ground from the cutoff relay 23 of the called line, 100 relays 93, 53, 68, 42 and 24 of the calling line. When relay 42 is deenergized its lower armature switch establishes circuit for the release magnet 99 of the idle link selector switch A by way of the previously closed 105 off normal switch 100, this circuit being apparent. The wipers of the idle link selector switch are restored to normal. When relay 54 is deenergized ground is established at its lower armature switch in connection 110 with the release magnet 101 of the employed connector switch, this circuit including the previously closed off normal switch 102. When circuit through the release magnet 101 is established the wipers of the connector switch are restored to normal. All 115 the equipment pertaining to the calling and called line and the apparatus that connected these lines is now restored to normal.

The relay 82 may be termed a supervisory 120 relay since it is of service in operating any equipment in bridge of the conductors extending to the calling station to indicate whether the called party has responded or not.

In the embodiment of the invention illustrated the instrument whose operation is effected by the relay 82 is the calling subscriber's telephone receiver, though obviously such an instrument might be a super- 125

- visory relay in a manually controlled link if such link were included in a telephone circuit. Prior to the response of the called subscriber a circuit is present which includes the grounded circuit interrupter 103, the 5 uppermost armature switch of relay 93 and its normal contact, the uppermost armature switch of relay 97 and its engaged contact, the winding of relay 82 and the grounded battery 21. The relay 82 is intermittently 10 operated to break the shunt about the resistance coil 104 occasioning distinct clicks in the telephone receiver of the calling subscriber, this resistance being then included 15 in series with the upper winding of relay 55. When the called subscriber responds and maintains his telephone receiver from its switch hook no click is manifested in the telephone of the calling subscriber owing to 20 the opening of the circuit at the upper armature switch of relay 97. If the called subscriber should restore his telephone receiver upon its switch hook before the calling subscriber restores his receiver upon its 25 switch hook another circuit is established which includes circuit interrupter 104, the uppermost armature switch of relay 93 and its alternate contact, the uppermost armature switch of relay 97 and 30 its contact, the supervisory relay 82 and the grounded battery 21. The circuit interrupters 103 and 104 are of different character so that the frequencies of interruption of the circuits of the relay 82 are different 35 whereby the calling subscriber will know, when the circuit including interrupter 104 is established, that the called subscriber has responded and restored his receiver upon its switch hook.
- 40 The equipment associated with the called line is similar to that associated with the calling line and similar parts have similar characters of reference. At the bottom of Fig. 5 the connector switch is illustrated by the rectangle 105 as it will not be necessary to repeat the illustration of the connector switch shown at the top of Fig. 5.
- 45 It will not be necessary to show the mechanism of the switches employed for connecting the operator's telephone with the calling lines, the switches employed for selecting idle link circuits, the connector switches employed for completing connections between calling and called lines, since such mechanism is well understood by those skilled in the art. Reference may be had to British Patent 1298 of 1910 and to Van Deventer's "Telephonology", page 530, for an understanding of the actual mechanical 55 design which may be employed.
- 60 It will be observed that the connector and link selector switches disclosed by me lack the usual sole switches that were hitherto so common in automatic practice.
- 65 While I have herein shown and particu-
- larly described the preferred embodiment of the invention I do not wish to be limited to the precise details of construction and circuit arrangement shown as changes may readily be made without departing from the 70 spirit of the invention.
- Having thus described my invention I claim as new and desire to secure by Letters Patent the following:—
1. A telephone system including telephone 75 lines extending from stations to an exchange; extensions for such telephone lines; an electro-magnetic line extending connecting device; controlling circuits for governing the association of said line extending connecting device and individual to the different positions of the switching parts of said line extending connecting device; operator controlled means for partially effecting modification of selected controlling circuits for the 80 purpose of arresting the switching parts of the line extending connecting device in the positions corresponding to the controlling circuits selected for modification; apparatus governed by said controlling circuits for arresting the switching parts of the line 85 extending connecting device and operated by such circuits when modified; and means governed by the line extending connecting device and brought into association with said controlling circuits individually whereby the apparatus for arresting the switching parts of the line extending connecting device is operated to arrest these switching parts in 90 positions corresponding to the modified controlling circuits, there being present electro-magnetic mechanism for operating the means governed by the line extending connecting device step by step, a circuit for this mechanism and means governed by the line 95 extending connecting device for interrupting this circuit to occasion the step by step operation of the electro-magnetic mechanism.
2. A telephone system including telephone 100 lines extending from stations to an exchange; extensions for such telephone lines; an electro-magnetic line extending connecting device; controlling circuits for governing the association of said line extending connecting device and individual to the different positions of the switching parts of said line extending connecting device; operator controlled means for partially effecting modification of selected controlling circuits for the 105 purpose of arresting the switching parts of the line extending connecting device in the positions corresponding to the controlling circuits selected for modification; apparatus governed by said controlling circuits for arresting the switching parts of the line 110 extending connecting device and operated by such circuits when modified; and switching means governed by the line extending connecting device and operating jointly with

the aforesaid operator controlled means for modifying selected controlling circuits and brought into association with said controlling circuits individually whereby the apparatus for arresting the switching parts of the line extending connecting device is operated to arrest these switching parts in positions corresponding to the modified controlling circuits, there being present 10 electro-magnetic mechanism for operating the switching means governed by the line extending connecting device step by step,

a circuit for this mechanism and means governed by the line extending connecting device for interrupting this circuit to occasion the step by step operation of the electro-magnetic mechanism.

In witness whereof, I hereunto subscribe my name this 7th day of October A. D., 1912.

MORTON L. JOHNSON.
